FRANK H. BURDSALL,

By *Arthur E. Paige*
Atty.

UNITED STATES PATENT OFFICE.

FRANK H. BURDSALL, OF CAMDEN, NEW JERSEY.

PACKAGE FOR PENS OR THE LIKE.

SPECIFICATION forming part of Letters Patent No. 655,894, dated August 14, 1900.

Application filed May 28, 1900. Serial No. 18,202. (No model.)

To all whom it may concern:

Be it known that I, FRANK H. BURDSALL, of Camden, in the county of Camden and State of New Jersey, have invented certain new and useful Improvements in Packages for Pens or the Like, whereof the following is a specification, reference being had to the accompanying drawings.

My invention relates to packages adapted to contain small articles of merchandise, such as pens and the like.

It is the object of my invention to provide a package which may remain sealed until opened by the purchaser, and thus indicate whether or not it has been tampered with, and which package when opened by the purchaser shall present a neat appearance and be adapted for continued use until its contents are exhausted.

To the ends aforesaid my invention consists of a rectangular box or casing open at one end and provided with a drawer in slideable relation therewith, together with means to prevent the drawer from being entirely withdrawn and certain frangible means by which the package is originally sealed intact, said sealing means being so constructed and arranged as not to interfere with the continued use of the package or to render the same unsightly when broken, as hereinafter described.

In the accompanying drawings, Figure 1 is a perspective view showing the under side of a package conveniently embodying my invention. Fig. 2 is a longitudinal sectional view of the package shown in Fig. 1, taken on the line A A, shown in Fig. 3. Fig. 3 is a sectional view taken on the line B B, shown in Fig. 2.

In said figures, 1 is the outer rectangular casing or box, which is open at the end 2 and provided with a drawer 3, which is arranged to slide longitudinally within said casing, said drawer being provided with a protruding tab 4 to conveniently effect its sliding movement. At the inner end of said drawer 3 and preferably at the bottom thereof is a stud 5, which is fixed with respect to the drawer conveniently by its bifurcated ends 6. Said stud 5 extends through the slot 7, which is longitudinally disposed in the casing 1, and said stud is provided with a circular flanged

head 8, which is wider than said slot and is arranged to slide upon the margins thereof. I prefer to construct said stud and its head 55 and shank of a single piece of metal to insure that said parts shall not be accidentally separated. Said stud is arranged as described to prevent the complete withdrawal of the drawer from the casing, and thus serves to 60 facilitate the manipulation of the package, which may be opened and closed many times before its contents are exhausted.

In order that the purchaser may be assured that he receives my improved package in its 65 original condition, I prefer to provide the same with a seal 9, which conveniently consists of an adhesive sheet or label of frangible fabric, such as thin paper. Said seal 9 is affixed by the manufacturer in the position 70 shown in Fig. 1—that is to say, it extends across the slot 7 in the path of the head 8 of the stud 5, and said seal being firmly secured to the margins of said slot any outward movement of the slide-drawer 3 serves to rupture 75 that portion of the seal extending across said slot, and thereby indicate that the package has been tampered with. However, said seal does not prevent the opening of the package by the purchaser, nor do the adherent fragments of it in any wise interfere with the continued use of the package and manipulation 80 of the drawer after the latter has been opened.

I have described the stud and slot elements 85 of my invention as being located in the under face of the package for the reason that I find it convenient to provide the other faces of the package with a label denoting the contents of the package, &c. It is obvious, however, that said slot-provided face may also be covered by a label exterior to said stud and seal.

I do not desire to broadly claim a slide-drawer package, as such devices are well-known in various arts. I believe it to be new, however, to provide a package having the combination of elements herein set forth, and therefore do not desire to limit myself to the precise construction and arrangement 95 thereof which I have shown and described, as it is obvious that various modifications may be made therein without departing from the essential features of my invention.

I claim—

1. In a telescopic box, the combination with an outer casing having a slot therein, of an inner drawer having a stud secured thereon, adapted to slide in said slot, and a frangible seal attached to the outer casing, across said slot, and adapted to prevent movement of said stud therein, substantially as set forth.
2. In a telescopic box, the combination with an outer casing having a slot therein, of an inner drawer fitted to slide in said casing, a stud adapted to slide in said slot, and comprising a circular flanged head overhanging the margins of said slot, a bifurcated shank upon said stud in integral relation with said head, by which said stud is secured to said drawer, and a frangible seal consisting of an adhesive sheet or label attached to the outer casing, across said slot, and adapted to prevent movement of the stud therein, substantially as set forth.
- 15

3. In a telescopic box, the combination with an outer casing having a slot therein, of an inner drawer fitted to slide in said casing, a stud adapted to slide in said slot, and comprising a circular flanged head overhanging the margins of said slot, a bifurcated shank upon said stud in integral relation with said head, by which said stud is secured to said drawer, and a frangible seal consisting of an adhesive sheet or label attached to the outer casing, across said slot, and adapted to prevent movement of the stud therein, substantially as set forth.

FRANK H. BURDSALL.
